United States Patent Office.

GEORGE C. TAFT, OF WORCESTER, MASSACHUSETTS, ASSIGNOR TO THOMAS H. DODGE, OF SAME PLACE.

Letters Patent No. 99,495, dated February 1, 1870.

IMPROVED MACHINE FOR DRILLING METALS.

The Schedule referred to in these Letters Patent and making part of the same.

To all whom it may concern:

Be it known that I, GEORGE C. TAFT, of the city and county of Worcester, and Commonwealth of Massachusetts, have invented certain new and useful Improvements in Drills, of which the following is a full, clear, and exact description, reference being had to the accompanying drawings, forming a part of this specification, in which—

Figure 1 represents a side view of my improved drill;

Figure 2 represents a section, on line A B, fig. 1; and

Figure 3 represents a vertical section through a part of the bed, and the device for holding the foot or stand in position.

To enable those skilled in the art to which my invention belongs, to make and use the same, I will proceed to describe it more in detail.

The nature of my invention consists—

First, in the combination, with the feed-arm, of an adjustable cam, as will be hereafter explained.

Second, in the combination, with the bed and foot or stand, of a holding-pawl or ratchet-piece, constructed as hereafter described.

In the drawings—

A is the bed, and B, the head, which may be cast with the bed A, if preferred.

The head B is bored or cored out, and a screw-thread cut therein, to receive the screw-thread *a* upon the tubular shaft C, to the outer end of which the ratchet-wheel D is secured.

E is the spindle-head, which is fitted with a recess or socket, in which the drill is to be inserted, where it is secured by the set-screw *b*.

The shank F of the drill-spindle extends through the tubular shaft C, and enters a socket in the inner end of the lever-piece G, where it is held by a set-screw *c*.

H is a feed-arm, the lower end of which is secured to a stud, *d*, which is fitted to rock and slide in the end of the bed-piece A, while to the upper end of the feed-arm is pivoted the pawl I.

The inner end *e* of the lever-piece G is made square, as shown in fig. 2, to receive the adjustable cam-piece J. The hole in the end *e* of the lever-piece G, which receives the end of the spindle-shank F, is not made in the centre, but eccentric thereto, and the same is true of the hole in the cam-piece J, which works in a slot, K, in the feed-arm H.

L is an adjustable lever, which is secured to the lever-piece G, by a set-screw, *f*.

From the foregoing description, it will be seen, that as the lever L is turned, the drill-spindle F will also be turned, while a rocking motion will be imparted to the feed-arm H, in consequence of the revolution of the cam-piece J in the slot K, since it is eccentric to the drill-spindle F.

It will be observed, by reference to fig. 2, that the cam-piece J just fills the space between the sides *g g* of the slot K, and that the sweep of the upper end of the feed-arm H will be greatest when the cam-piece J

is arranged upon the square end *e* of the lever-piece G, as shown in fig. 2, and that the sweep will be shortened if the cam-piece J is slipped off, and turned a quarter way around before it is replaced, while, if it is turned half way around, the feed-arm will remain at rest, the cam-piece J being then concentric to the centre of the drill-spindle F.

From the foregoing description, it will be seen that the feed can be varied very readily, by simply turning the cam-piece J on the many-sided part *e*, and which part may be made with three, four, or more sides, the hole in the cam-piece being made to conform to the shape of said part *e*.

The length of the feed-arm H, and the teeth *h*, should be graduated, or made to give the desired feed to the tubular feed-shaft C.

As the shaft C is turned, it feeds forward the drill-spindle, by pressing against the head E.

The stud *d* is fitted to slide in and out, as the shaft C is run in and out.

Upon the bed A are cast teeth M, into which the teeth N, on the stop-piece O, catch, when said piece is dropped down, as shown in fig. 3, thereby holding the foot or stand P in place during the operation of drilling the article or material, which rests, and is pressed against the front of the stand P.

When it is desired to move the stand back or forward, the catch or stop-piece O can be raised by means of the thumb-piece Q, a space or recess, *m*, being formed in the base of the stand P, to receive the stop-piece O, as fully indicated in fig. 3.

It will be understood that the flanges *n* of the stand P are fitted to slide under the flanges *p* of the bed A.

By the use of the stop-device, shown in the drawings, the stand P can be adjusted very quickly, while at the same time the objections to the use of a set screw, to hold the stand in place, are obviated.

The stop-piece O is made to fit closely in the recess in the base *m*, so that the stand is retained in a very secure and central position.

Having described my improvements in drills,

What I claim therein as new, and of my invention, and desire to secure by Letters Patent, is—

1. The combination of cam J, having a many-sided hole formed therein, with a many-sided supporting-piece, *e*, and the shank or spindle F, said parts being arranged in relation to each other, substantially as and for the purposes set forth.

2. The combination, with the feed-arm H, and lever-piece G, *e*, of the cam-piece J, substantially as and for the purposes set forth.

3. The combination, with the stand P and bed A, of the stop-piece O Q, said parts being constructed substantially as and for the purposes set forth.

GEO. C. TAFT.
